A. H. NOBLE

LIP STICK HOLDER

Filed Dec. 10, 1926

UNITED STATES PATENT OFFICE.

ARTHUR H. NOBLE, OF PAWTUCKET, RHODE ISLAND, ASSIGNEE TO THEODORE W. FOSTER & BROTHER COMPANY, OF PROVIDENCE, RHODE ISLAND.

LIP-STICK HOLDER.

Application filed December 10, 1926. Serial No. 153,815.

This invention relates to certain new and useful improvements in lip stick holders, and the primary object thereof is to provide novel means, which can be easily and quickly operated, for effecting movement of the lip stick into and out of the holder, and for also reliably retaining the lip stick within the holder, so as to prevent accidental movement thereof when the holder is being carried or is not in use.

The invention still further aims to provide means of the character mentioned which is of simple and economical construction and which does not detract from the appearance of the usual tubular or cylindrical holder.

In the drawings:—

Fig. 1 is an elevation of the holder in closed position of the parts;

Fig. 2 is a section on line 2—2 of Fig. 1;

Fig. 3 is a view of the holder in partly open position; and

Fig. 4 is a section on line 4—4 of Fig. 1.

In proceeding in accordance with the present invention, the holder is composed of a cylindrical or tubular body 1 which has a closed bottom 2. The body 1 is formed with an elongated slot 3 which extends axially thereof as shown in Figs. 1 and 2. A socket member 4 of cup shape is employed to receive the lip stick L, the socket having an inwardly struck seat 5 for engagement with the lip stick to retain the latter in the socket. The socket or thimble 4 is provided with a loop 6 in the form of a U-shaped member the legs of which extend through openings provided therefor in the thimble, the free ends of the legs being turned outwardly at 7 so as to hold the loop 6 in position. A cap 8 is provided and which is slidably engaged with the open upper end of the holder 1 and which is formed with an arm 9 integral therewith, the arm 9 being provided with an opening receiving loop 6, whereby to form a hinged or pivotal connection between the thimble 4 and the arm 9. The loop 6 is freely slideable along the length of the slot 3.

With the parts in the position of Figs. 1 and 2, and in order to project the lip stick

out of the holder, the cap 8 and its arm 9 are slid outwardly from the holder so as to disengage the cap from the holder, whereupon the cap and its arm are swung outwardly, as shown in Fig. 3 to permit the arm 9 to be moved along the slot so as to thereby cause movement of the thimble and therewith the lipstick, axially of the housing, so as to project the lip stick out of the holder. The arm 9 can be swung downwardly to its extreme of movement thereby to engage and lie parallel to the holder, which thus enables the arm to be grasped by the fingers of the user so as to provide a longer handle for the holder.

It will be seen that the arm 9, when the parts are in closed position, conforms to and lies flat against the body, thus not detracting from the usual appearance of cylindrical lip stick holders and at the same time providing a compact arrangement.

Having thus described my invention what I claim as new and desire to secure by Letters Patent is:—

1. In a lip stick holder, a tubular body having a longitudinal slot and having a closed end and an open end, a closure for the open end slideable on the body, a lip stick carrier slideable in the body, a loop secured to the carrier and extending through and being slideable in the slot of the body, and an arm carried by the closure and having an opening through which the loop extends so as to hingedly connect the arm to the carrier.

2. In a lip stick holder, a tubular body having a closed end, an open end and a longitudinal slot, a closure for the open end slideable on the body, a lip stick carrier slideable in the body, an arm carried by the closure and a connection between the arm and carrier extending through the slot and secured to a side of the carrier and hingedly mounting the arm, said slot terminating adjacent to the open end of the body and having said terminal engageable with the connection to limit outward movement of the carrier.

In testimony whereof I have signed my name to this specification.

ARTHUR H. NOBLE.
